A gas turbine arrangement for ships in which a low temperature turbine using low grade fuel is mounted above the deck and is directly coupled to a compressor for a second turbine mounted in the engine room which operates at high temperature and with high quality fuel. The entire output of the second turbine drives the ship propeller, preferably through reduction gearing. The compressed air from the above-deck turbine may be heated by the exhaust gases from the below-deck turbine. The above-deck turbine may be a two-stage arrangement having an intercooler between the two stages of compression. Additionally a bleeder system and heat exchanger may be incorporated in the output of the first compressor.

FIG.8

COMBINED GAS TURBINE

The present invention relates to a combined gas turbine effectively used for ship.

The gas turbine is light in weight and small in size but large in output, and thereby widely used for aircraft. However application of gas turbine to ship is extremely limited and only found specifically in naval craft. The reason for this is that the use of low grade fuel is difficult because of increase of fuel expense. Further reason is that suction air volume of the gas turbine per output is large, thereby a large amount of exhaust gas generated and a large sectional area of exhaust ducts required in spite of the fact that the gas turbine engine itself is small in size. These factors are of course disadvantageous to apply the gas turbine to ships.

The present invention has for its object to remove the above mentioned disadvantages, and is characterized in that two or more gas turbines are combined to form a composite cycle, so that amount of suction air introduced in the output turbine is decreased, and thereby decreasing cross-sectional area of the suction and the exhaust ducts thereof.

The combined gas turbine in accordance with the present invention are such composed that an air compressor is driven by means of an independent gas turbine which consumes chiefly low grade fuel such as Bunker C heavy oil or Heavy Marine Fuel Oil and high pressure air discharged from the compressor is introduced into combustor of output turbine and then the produced high temperature and high pressure gas is introduced into the output turbine to obtain output.

In the drawings:

FIGS. 1a and 1b are schematic diagrams showing conventional gas turbines;

FIG. 2 is a schematic diagram showing the present invention;

FIG. 3 is a schematic diagram showing a case in which the present invention is applied to ships; and

FIGS. 4 through 8 are schematic diagrams showing other embodiments of the present invention applied to ships respectively.

Referring to the drawings, in accordance with the present invention ordinary gas turbines A and B shown in FIGS. 1a and 1b are combined to compose one unit as shown in FIG. 2. The combined gas turbine comprises a compressor side C and an output side D. The compressor side comprises a compressor C₁, combustor B₁, output turbine T₁ and compressor C₂ connected to the output shaft of the turbine T₁. The high pressure air discharged from the compressor C₂ is introduced in the combustor B₂ of the output side turbine to drive the turbine T₂.

In this case, when the output of turbine is represented by W_t and the required power for compressor is W_c, the following equation must be held:

$$W_{c2} = W_{t1} - W_{c1}$$

From this relation, it will be seen by simple calculation that the power output HP₃ is equal to the sum of output HP₁ of the gas turbine A and output HP₂ of the gas turbine B. That is to say, with respect to the output, the present invention does not show a profit in particular. However, the economy of fuel cost and the reduction of space for the suction and the exhaust ducts for installing the turbine in the ship are greatly affected by the present invention. The reasons will be described

hereinafter. The output of the gas turbine increases with the temperature of gas in the combustor B thereof. If low grade fuel such as Bunker C heavy oil or Heavy Marine Fuel Oil is used, ash is generated, and turbine blades are corroded at high temperature. Therefore, gas temperature is at present considered not to exceed 750°C.

In the combined gas turbine according to the present invention, flow rate of air introduced into the combustor B₁ by means of the compressor C₁ is about 5 two point three times as much as that of the combustor B₂. This means that fuel consumption ratio of the combustor B₁ is about 70 percent of whole fuel consumption of the combined turbine. The present invention can provide an economical combined turbine by using a low grade fuel in the combustor B₁ of large fuel consumption ratio, even if the fuel consumption rate per output is increased owing to low gas temperature below 750°C. While, high quality fuel such as light oil is used in the combustor B₂, high power output is obtained by

10 raising the gas temperature.

15 Consideration is now given to amount of air necessary for obtaining a required power output HP₃. In the conventional single turbine, about two-thirds of output of the turbine is allotted for driving the compressor and

20 about one-thirds of the output is available for use. This situation prevails also in the turbine of the present application. The turbine T₂ of the present invention need not drive the compressor and suffices to generate about one-thirds of power output comparing with the conventional turbine having the same output HP₃, which means that the amount of air to be supplied to the combustor B₂ decreases to about one-thirds of conventional case. Accordingly, the cross-sectional area of the duct leading to the combustor B₂ also becomes smaller.

cost is improved as a whole by using low grade fuel in the large ratio to whole fuel consumption, as well as the cross-sectional area of the air suction and exhaust ducts can be remarkably reduced. Besides, since the gas turbine consuming low grade fuel is located above the deck, maintenance of the gas turbine is easy.

What is claimed is:

1. A combined gas turbine drive for a ship having a hull closed at the top by a deck, a propeller for driving the ship having a propeller shaft extending longitudinally through the bottom of the hull, and an engine room in the bottom of the hull below said deck for housing the controls of the ship for driving the propeller, said drive for the ship comprising a first gas turbine, a combustor utilizing compressed air and fuel to generate the gas for driving said first turbine, means mounting said first turbine and combustor above the deck of said ship, a second turbine having an output shaft coupled to said propeller shaft, means mounting said second turbine below the deck of said ship in said engine room, a combustor for feeding combustion gases to said second turbine, means to supply a different fuel and compressed air to said combustor, said combustion burning said fuel and generating said combustion gases, a compressor for supplying compressed air to said sec-

ond combustor, means mounting said compressor on the deck or above the deck of the ship, means coupling the drive shaft of said first turbine to said second compressor whereby said compressor is driven by said first turbine, and high pressure air lines extending from the compressor above the deck of the ship to the combustor for the second turbine.

2. A combined gas turbine drive according to claim 1 wherein said combustor for supplying gas to said second turbine is operative at high temperature and with high quality fuel and said combustor for supplying gas to said first turbine is operative with low grade fuel such as Bunker C heavy oil or Heavy Marine Fuel Oil.

3. A combined gas turbine drive for ships according to claim 1 including means to couple the entire output of said second turbine to the ship propeller.

4. A drive according to claim 3 wherein said coupling means consists of reduction gearing.

5. A drive for ships according to claim 1 including a heat exchanger to receive exhaust gases from the second turbine, and means to direct compressed air from said compressor through said heat exchanger prior to passing into said combustor.
